UNITED STATES PATENT OFFICE

2,181,360

LEADER PIN OILER

Emil A. Baumbach, Chicago, Ill.

Application March 4, 1938, Serial No. 193,865

6 Claims. (Cl. 308—5)

This invention relates to improvements in oilers and more particularly to devices designed for lubricating the leader pins used in connection with punch press die sets. The device is adapted to provide an efficient oiling means for leader pins and may be used in connection with any of the usual die sets without material change in any of the elements of the set. The device is adapted to be self-supporting and automatic in operation when once inserted in place and to retain a supply of oil or other lubricant and keep the pins properly lubricated at all times.

It is an object of the present invention to provide an oiler which will apply lubricant over the cylindrical surface of the leader pins with each operation of the punch press and which may be so positioned with respect to the punch holder and shoe that it will not interfere with the usual operation of the die sets. Also provision is made whereby an additional supply of lubricant may be added as required.

A further object is the provision of a leader pin oiler which may be applied to any ordinary die set and will be of few parts, cheap to manufacture, easy to assemble, and will not easily get out of order in use.

The device also may be manufactured and sold independently of the die set and may be applied thereto by the user without change in the die set or oiler and without the use of tools or any auxiliary means for securing the oiler in place.

Further objects will be apparent from the specification and the appended claims.

In the drawing,

Fig. 1 is a vertical sectional view through a die set and one of the oilers and illustrates one embodiment of the invention.

Fig. 2 is an expanded perspective view in longitudinal section of the oiler housing.

Fig. 3 is an enlarged fragmentary sectional view through the assembled housing and corresponds to a portion of the housing shown in section in Fig. 1.

Fig. 4 is a top plan view of one form of wick adapted for use in the oiler housing.

Referring to the drawing in detail, the embodiment illustrated comprises a die shoe 1 having leader pins 2 preferably rigidly secured therein and extending upwardly in parallel relation through suitable holes in a punch holder 3. The punch holder 3 is preferably provided with suitable hardened bushings 4 through which the leader pins 2 extend. Each of the pins may be provided with a suitable oiler which is supported thereon and which comprises a ring-like sheet

metal container member or housing member 5 having an inner upturned flange 6 and an outer upturned flange 7 spaced therefrom to provide an annular trough therebetween. This construction provides an annular lubricant chamber 8 in the container.

A container cover 9 is provided and is constructed very similar to the container 5, but slightly smaller in outside diameter and is provided with an inner downwardly extending flange 10 and an outer downwardly extending flange 11, which latter substantially corresponds in width to flange 7 of the container 5. The cover member 9 is of a suitable size to telescope within the container 5 as illustrated and to form a wick holding lubricant chamber therebetween. A ring-like wick 12 is inserted between the members 5 and 9 and, when these members are telescoped together, the wick member is compressed in such a manner that an annular portion extends inwardly between the flanges 6 and 10 in a position to contact with a leader pin when the device is placed thereon.

The wick may be a ring or washer of felt or other suitable material such as illustrated in Fig. 4, or it may be merely a suitable strip of a desired cross section and of suitable length to extend completely around the leader pin.

A body member 13 is also provided and, if desired, may be identical with the member 5. In fact, an identical member may be used and merely inverted as illustrated in Fig. 3 and soldered or otherwise secured to the bottom of the member 5 as shown at 14. It will be understood that, by this construction members 5 and 13 may be interchangeable and may be formed by the same tools thereby providing a very cheap construction.

A coil spring 15 is provided which is of sufficient diameter to receive the leader pin 2 therein and the oiler housing is supported on the upper end of this spring as illustrated in Fig. 1. If desired, the upper end of the spring may be secured in the housing 13 by soldering or any other suitable means. The spring preferably is of sufficient length to always retain the housing against the punch holder during any position of the holder so that the oiler housing follows the holder at all times and the felt wick effectively lubricates the pin over its length with each operation of the punch press.

An oil hole 16 is provided through the flange 7 of the housing member 5 and a corresponding hole 17 is provided through the flange 11 of the cover member 9. These holes are positioned so that they are in alignment when the device is

50

55

assembled so that lubricant may be applied to the wick as required.

The device provides many advantages over ordinary methods in that it may be applied to ordinary die sets without change in any part of either the set or the oiler, and without the use of special tools. The oiler device may easily be removed and replaced and new wicks may be inserted by merely removing the cover member 11.

10. Modifications may be made without departing from the spirit of the invention. It is desired, therefore, that the invention be limited only by the prior art and the scope of the appended claims.

15. Having thus described this invention, what is claimed and desired to be secured by Letters Patent is:

1. A leader pin oiler for die sets comprising a hollow annular housing comprising two ring-like sheet metal members having wide outer flanges telescoped one within the other, said members having comparatively narrow inturned inner flanges spaced from said outer flanges and from each other to provide an annular chamber with an annular slot between the edges of said inner flanges, and a wick in said chamber having an annular portion extending from said opening to contact a leader pin when said housing is telescoped thereover, and an elongated compression spring secured to one of said members to resiliently support said oiler on a die shoe.

2. In a leader pin oiler, a lubricant housing comprising a cup-shaped sheet metal container member having an axial opening to receive a leader pin, a comparatively narrow inturned flange around said opening to provide an annular lubricant trough, an inverted cup-like sheet metal cover member having a similar axial opening and a similar comparatively narrow inturned inner flange, said cover member being telescopically mounted on said container member whereby said inner flanges are spaced to provide an annular slot between said inner flanges, means between said members for conducting lubricant from said trough to said leader pin, and an elongated coil spring secured to said container member in axial relation thereto.

3. In a leader pin oiler, a lubricant housing comprising a cup-shaped sheet metal container member having an axial opening to receive a leader pin, a comparatively narrow inturned flange around said opening to provide an annular lubricant trough, an inverted cup-like sheet metal cover member having a similar axial opening and a similar comparatively narrow inturned inner flange, said cover member being telescoped within said container member whereby said inner flanges are longitudinally spaced to provide an annular slot between said inner flanges, an annular wick

filling a substantial part of the annular chamber in said housing and compressed between said members and extending through said slot to conduct lubricant to said leader pin when telescoped thereover, and an elongated coiled spring secured to one of said members in axial relation thereto and of a diameter not substantially less than the axial opening through said housing.

4. A leader pin oiler for die sets comprising an annular housing arranged to be slidably mounted on a leader pin between the die shoe and the punch holder, said housing comprising two annular trough-like members having wide outer flanges and relatively narrow inner flanges, said members being telescoped together in reversed relation whereby their telescopic relation is limited by one of the outer flanges, and the inner flanges are spaced to provide an annular slot therebetween, a wick in the chamber formed by said members and having an annular portion extending through said slot, a third member substantially identical with one of said housing members and secured thereto in inverted axial relation, and an elongated coil spring secured in said last member in axial relation therewith.

5. A leader pin oiler for die sets comprising a hollow annular housing comprising two ring-like sheet metal members having wide outer flanges telescoped one within the other, said members having comparatively narrow inturned inner flanges spaced from said outer flanges and from each other to provide an annular chamber with an annular slot between the edges of said inner flanges, and a wick in said chamber having an annular portion extending from said opening to contact a leader pin when said housing is telescoped thereover, and an elongated compression spring to resiliently support said oiler on a die shoe.

6. In a leader pin oiler for die sets wherein a movable and a stationary die set members are positioned for relative movement toward and from each other and are retained in operating alignment by leader pins, a hollow annular wick housing comprising a formed ring-like sheet metal member having a hollow wick chamber and adapted to surround and move axially along one of the leader pins, said wick housing having an annular inwardly opening slot communicating with the surface of said leader pin, an oil-bearing wick member in said chamber and having a part extending inwardly through the annular slot for lubricating engagement with the leader pin, and a resilient member in adjacent axial alignment with the wick housing and urging the same into continuous engagement with one of said die set members throughout the course of its relative movement upon said leader pin.
